PIPE CLAMP

Louie J. Marchese, 5116 N. 17th St., Phoenix, Ariz.
85016, and Robert A. Hildebrandt, P.O. Box 42, Queen
Creek, Ariz. 85242

Filed Oct. 29, 1971, Ser. No. 194,087

Term of patent 14 years

Int. Cl. D8—08

U.S. Cl. D8—229

FIG. 1

FIG. 2

FIG. 1 is a perspective view of a pipe clamp embodying our new design.

FIG. 2 is a partial view of the pipe clamp with a part of the latch structure broken away to show the latch tongue.

We claim:

The ornamental design for a pipe clamp, as shown and described.
